UNITED STATES PATENT OFFICE.

ELIJAH MCCOY, OF DETROIT, MICHIGAN, ASSIGNOR OF ONE-HALF TO GEORGE W. MOULDEN, OF DETROIT, MICHIGAN.

DESIGN FOR A VEHICLE WHEEL TIRE.

Application filed May 13, 1922. Serial No. 2,232. Term of patent 7 years.

To all whom it may concern:

Be it known that I, ELIJAH MCCOY, a citizen of the United States, residing at Detroit, in the county of Wayne and State of Michigan, have invented a new, original, and ornamental Design for Vehicle Wheel Tires, of which the following is a specification, reference being had to the accompanying drawing, forming part thereof.

In the drawing, Fig. 1 is a development of the bearing surface of a tire embodying my design. Fig. 2 is a perspective view of the tire. Fig. 3 is a transverse section of the tire.

I claim:

The ornamental design for a vehicle wheel tire as shown.

ELIJAH MCCOY.
